UNITED STATES PATENT OFFICE.

ROBERT DUNLAP, OF NEW YORK, N. Y.

DESIGN FOR A HAT-LINING.

SPECIFICATION forming part of Design No. 13,372, dated October 31, 1882.

Application filed September 29, 1882. Term of patent 7 years.

To all whom it may concern:

Be it known that I, ROBERT DUNLAP, a citizen of the United States, residing at New York, in the county and State of New York, have invented and produced a new and original Design for Hat-Linings, of which the following is a specification, reference being had to the accompanying drawings.

The novel feature of this design consists of a flat tip, and radial corrugations extending from the circumference of this tip to the outer edge of the lining.

In the accompanying drawings, Figure 1 represents a sectional inside view. Fig. 2 is a vertical cross-section.

Similar letters indicate corresponding parts.

In these drawings, the letter A designates the flat tip, which may be round, oval, or of any desirable shape, and which is fastened in the

interior of the lining B. From the edge or circumference of the tip extend a series of radial corrugations, C, to the outer edge of the lining, the point from which these corrugations radiate being the center of the lining.

What I claim as new, and desire to secure by Letters Patent, is—

The design for a hat-lining, consisting of a flat tip, and of radial corrugations extending from the edge or circumference of the tip to the outer edge of the lining, as shown and described.

In testimony whereof I have hereunto set my hand and seal in the presence of two subscribing witnesses.

ROBT. DUNLAP. [L. S.]
